United States Patent

Des. 234,525
Patented Mar. 18, 1975

234,525

STUFFED TOY

William J. Maloney II, East Aurora, N.Y., assignor to
The Quaker Oats Company, Chicago, Ill.

Filed July 9, 1973, Ser. No. 377,523

Term of patent 14 years

Int. Cl. D21—01

U.S. Cl. D34—4 R

FIG. 1

FIG. 2

FIG. 1 is a front prospective view of a stuffed toy showing my new design; and

FIG. 2 is a top plan view thereof.

I claim:

The ornamental design for a stuffed toy, substantially as shown.
